Primary Examiner — Susan Bennett Hattan*Assistant Examiner* — Brett Miller(74) *Attorney, Agent, or Firm* — Mark E. Bandy; Rankin, Hill & Clark LLP(57) **CLAIM**

The ornamental design for a swing arm, as shown and described.

DESCRIPTION

FIG. 1 is a front left perspective view of a swing arm. FIG. 2 is a left side view of the swing arm of FIG. 1. FIG. 3 is a right side view of the swing arm of FIG. 1. FIG. 4 is a front elevational view of the swing arm of FIG. 1. FIG. 5 is a rear elevational view of the swing arm of FIG. 1. FIG. 6 is a top plan view of the swing arm of FIG. 1. FIG. 7 is a bottom plan view of the swing arm of FIG. 1; and, FIG. 8 is a front elevational view of the swing arm of FIGS. 1-7 illustrating a possible use. The dashed lines in FIGS. 1-8 are for illustrative purposes only showing environmental subject matter and form no part of the claimed design.
